United States Patent Office.

JOSEPH SAWYER, OF SEBEWAING, MICHIGAN.

Letters Patent No. 96,841, dated November 16, 1869.

IMPROVED DETACHABLE BUOYANT SHIP'S DECK.

The Schedule referred to in these Letters Patent and making part of the same.

To whom it may concern:

Be it known that I, JOSEPH SAWYER, of Sebewaing, in the county of Huron, and State of Michigan, have invented a new and useful Improvement in Detachable Buoyant Hurricane-Deck; and I do declare that the following is a true and accurate description thereof, reference being had to the accompanying drawings, and to the letters of reference marked thereon, and being a part of this specification, in which—

Figure 1 is a perspective view of my improved floating deck, attached to, and forming part of the hurricane-deck of a steamer.

Figure 2 is a section of the same, on the line *x-x* in fig. 1.

This invention relates to an improved construction of a portion, or the entire hurricane-deck or cabin-roof of a steam-vessel, so that the same may readily be detached from the vessel, should she sink, and, being buoyant, will serve as a raft, to preserve the lives of the passengers and crew.

It consists in constructing a part or the whole of the hurricane-deck with double walls, forming compartments, in which air-vessels or cork may be placed, to increase the buoyancy of the raft, for such it becomes when the vessel sinks, and in the method of securing it to the walls of the cabins and stanchions, so that, when necessary, it may be quickly detached therefrom.

In the drawings—

A represents a section of the cabin-deck of a steamer, and

B, a section of the hurricane-deck, supported by and secured to the stanchions C, in the usual manner.

D represents my improvement, forming an extension toward the stern of the hurricane-deck C; and consists of a deck proper, *a*, and a ceiling, *b*, secured to the ordinary deck-carlings, and enclosed by a side wall, *c*, forming compartments, which may be calked air-tight, or filled with cork, E; or air-tight vessels of sheet-metal may be placed within the compartments, to give the deck greater buoyancy, when it is required to be used as a raft.

The detachable deck rests upon the cabin-walls (which are not shown) and upon the stanchions F, which are provided with proper shoulders for that purpose.

The upper ends of the stanchions are turned to a smaller diameter than their bodies, and project up through the deck, as at *f*, and the deck is secured in place by keys, *g*, driven through slots in the upper ends of said stanchions.

G is a locker, closed by a hatch, in the deck. In the locker, a supply of provisions, matches, lanterns, and signals, should be kept ready for use in emergency.

A proper railing should also be erected around the edge of the deck, to prevent persons on it from being washed off, when used as a raft.

Should the vessel to which my improvement is applied, from any cause, be about to founder, the passengers and crew retire to my deck, the keys *g* are then withdrawn from the slots in the stanchions, and as the vessel goes down, the raft floats on the surface of the water, bearing its precious load in safety.

The life-boats belonging to the vessel should not all be suspended from the ship's davits, but a part of them should rest on cradles on the deck or raft, and secured thereto by their painters, ready to be launched therefrom after the vessel has gone down.

What I claim as my invention, and desire to secure by Letters Patent, is—

1. The detachable double-walled buoyant deck D, provided with compartments for receiving air-vessels, cork, or other buoyant material, and secured to the stanchions or cabin-walls, in any convenient manner that will permit of its being readily detached therefrom.

2. In combination with the deck D, a locker or receptacle, G, formed therein, for the purpose specified.

JOSEPH SAWYER.
